UNITED STATES PATENT OFFICE.

JOSEPH SAMUEL BEEMAN, OF LONDON, ENGLAND.

CIGARETTE-MOUTHPIECE-APPLYING MACHINE.

SPECIFICATION forming part of Letters Patent No. 645,287, dated March 13, 1900.

Application filed June 7, 1898. Serial No. 682,850. (No model.)

To all whom it may concern:

Be it known that I, JOSEPH SAMUEL BEEMAN, a subject of the Queen of England, residing at London, England, have invented 5 certain new and useful Improvements in Cigarette-Mouthpiece-Applying Machines, (for which I have obtained Letters Patent in England, No. 11,682, dated May 23, 1898,) of which the following is a specification.

10 This invention relates to coating or coating and applying machines in which paper, cork, tobacco-leaf, or similar substances are used. The apparatus may be employed for various kinds of coating—such as, for example, applying paste or other adhesive matter, water to moisten material which has been previously coated with adhesive matter, or coloring-matter in a dry or liquid condition. It may also be used for applying the material coated to the article which is to receive it.

15 A particular application of this invention is illustrated in a machine for coating and applying tips to cigarettes, and I have selected a machine of that type for special description and illustration in the present specification and drawings.

20 A machine embodying this invention comprises a wetted "retainer" for holding the "strip" of material while it is being coated, a "coater" for applying the adhesive medium, water, coloring, or other coating to the strip, and a "lifter" for detaching the coated strip from the retainer. In conjunction with these features a holder is sometimes provided which 25 is preferably capable of gripping the article, and a "finisher" may also be employed to smooth the strip after it has been applied to the article.

25 The retainer comprises a surface or surfaces capable when wetted of holding a strip of material against the tendency of the coater to displace it while the coating is being applied to it. The retainer is furnished either with grooves, holes, or other accommodation 40 to receive the lifter, which is so formed and operated that the strip of material is raised by it from the wet surface of the retainer. The lifter according to this invention presents a comparatively-dry surface to the strip 45 to be moved and effects such removal in a direction normal, or approximately so, to the wetted surface. During the coating of the

strip the adhesion between it and the wetted surface of the retainer is greater than that between the coater and the coated surface of 55 the strip, and if the coated surface of the strip is momentarily pressed by the lifter into contact with the article to which it is to be applied the adhesion between the latter and the coated surface is greater than any which 60 would obtain between the uncoated surface and the contiguous face of the lifter.

In cases where the coated strip is not to be immediately applied to an article any convenient means may be used to remove the coated 65 strip from the lifter.

In the accompanying drawings, Figure 1 is a plan of one construction of a cigarette-tipping machine provided with improvements according to this invention. Fig. 2 is an end 70 elevation, partly in section, on the line 2 2 of Fig. 1. Fig. 3 is a transverse vertical section on the line 3 3 of Fig. 1. Fig. 4 is a longitudinal vertical section showing a portion of the machine in further detail and to a larger 75 scale. Fig. 5 is an elevation showing another portion of the machine, also to a larger scale. Fig. 6 shows a detail of the machine on a larger scale.

Like letters indicate like parts throughout 80 the drawings.

A is a bed-plate upon which all stationary parts of the machine are rigidly mounted.

B B' B² are standards which carry in bearings B³ a shaft C, from which the various 85 parts of the machine are operated. The shaft C has five cams D, D', D², D³, and D⁴ mounted upon it and also carries a gear-wheel E. It may be driven by any convenient means, such as a pulley C'.

90 F is a holder comprising a tube F', having an internal spring F², which enables it to grip the cigarette. The holder F rotates in bearings F³ on the standard B². It is driven from the gear-wheel E by means of gear-wheels 95 E' and E², the latter being mounted upon the tube F'.

Fig. 6 shows the rotating cigarette-holding tube in further detail. In this construction the light spring F² is secured to the collar F⁴ upon the tube F' by means of a small screw F⁵. It is, however, to be understood that other means may be employed for gripping the cigarette in the tube. For instance, the

tube may be made of light springy metal and provided with a slot or slots, so that it exerts a slight pressure upon the cigarette when the latter is introduced into it.

5 It is found convenient to arrange the diameters of the gear-wheels E E' E² so that the holder F makes approximately six revolutions to one revolution of the shaft C.

G is a retaining device illustrating one form of retainer for holding the strip of material while it is being coated. It comprises three hexagonal plates G', having their edges covered with rubber or like material and capable of rotation about an axis G², carried by a frame G³, which is reciprocated upon guides G⁴ by means of the cam D', acting through the levers G⁵ and G⁶. The lever G⁶ carries a friction-roller G⁷, which works in a cam-groove D⁵ in the cam D'. A trough G⁸, containing water or other liquid, is so placed that the lower part of the hexagonal plates G' is immersed. The axis G² carries a ratchet-wheel G⁹, having six teeth, and also another wheel G¹⁰, which is provided with six flats or hollows on its circumference. A spring H, carried upon the under side of a plate J, supported by standards B² and B⁴, engages with a tooth of the ratchet-wheel G⁹ when the frame G³ returns and forces the ratchet-wheel G⁹ around to an amount equal to one tooth. The hexagonal plates G' turn with the ratchet-wheel G⁹, and thus once in every complete reciprocation of the retaining device G a fresh-wetted edge of the hexagonal plates G' is turned uppermost. An opening J' is formed in the plate J, through which the edges of the plates G' pass. A spring G¹¹, fixed to the frame G³, presses upon the flats or hollows in the wheel G¹⁰, so that during the reciprocation 40 of the retaining device G the hexagonal plates G' are prevented from revolving.

K is a lifting device illustrating one form of lifter and comprises two fingers K', which are carried by a spring K² upon the plate J. A hook K³ is attached to the fingers K', and upon the retaining device G moving backward, this hook K³ is caught by a spring-rail G¹², carried by the frame G³, and the lifting device K is consequently depressed until released by passing off the other end of the spring-rail G¹². The fingers K' are so disposed that they pass into the spaces between the hexagonal plates G' as the latter reciprocate. The spring K² is furnished with a pin K⁴, which works in a hole in the plate J, and a screw K⁵ is provided, by which the height to which the lifting device K rises may be adjusted.

L is a smoothing device or finisher. It comprises a flat spring L', carrying a plate L² at one end and fixed at the other end to a bent lever L³. This lever L³ is pivoted at L⁴ and carries a friction-roller L⁵, upon which the cam D operates. The return of the lever L³ is caused by the action of a spring L⁶, one end of which is fixed to the lever L³ and the other to a pin L⁷, fixed in the standard B².

M is a pasting device and comprises a cylinder M', having a piston M². The piston-rod M³ is formed with a left-handed screw, upon which a screwed collar M⁴ works and carries a ratchet-wheel M⁵. The cylinder M' is furnished with a longitudinal slot M⁶ in its under side near its closed end. It is supported by a bracket M⁷ and held in place by a clip M⁸. The end of the piston-rod M³ is held in a slot in an arm M⁹, attached to one of the brackets B⁵. A felt roller M¹⁰ is placed below the slot M⁶ in the cylinder M² and rotates, being driven by gear-wheels E³ and E⁴ from the wheel E², carried upon the tube F'. The relation between the diameters of the gear-wheels E² and E⁴ is such that the peripheral speed of the felt roller M¹⁰ is slightly greater than the rate of travel during advancement of the retainer G. A curved plate M¹¹ is attached to the lower portion of the cylinder M' and extends partly around the roller M¹⁰. The ratchet-wheel M⁵ is moved by an amount equal to one tooth for each complete revolution of the shaft C. This is caused by the cam D² acting upon a pivoted lever N through a friction-roller N' against the action of a spring N². The lever N terminates in a spring N³, which catches in the teeth of the ratchet-wheel M⁵ when it moves downward, but slips past them when it returns. A light spring M¹², carried upon the arm M⁹, serves to prevent the motion of the wheel M⁵, except when actuated by the lever N. The screwed collar M⁴, upon which the ratchet-wheel M⁵ is mounted, bears against the arm M⁹, and thus each time the wheel M⁵ is turned the piston M² is caused to advance slightly into the cylinder M'. 105

O is a hopper into which the cigarettes are placed. It is carried by two of the standards B⁵ and a third standard B⁶. The hopper O is provided with a plunger O', which is reciprocated by a lever O², pivoted upon the standard B⁶ and operated through a friction-roller O³ from the cam D³, which acts in opposition to a spring O⁴.

The cigarettes pass from the hopper O to a trough P, mounted in line with the holder F. 115

R is a plunger sliding freely in bearings in the standards B⁵. It is reciprocated by means of a lever R', one end of which is pivoted to the standard B⁵. The other end of the lever R' works in a guide R², fixed upon the plunger R. The motion of the lever R' is caused by the cam D⁴ acting through a friction-roller R³ and opposed by the action of the spring R⁴. The function of the plunger R is to cause a cigarette to pass from the trough P to the holder F. 125

In order that when desired the machine may be rotated without cigarettes being fed into the holder F, a catch O⁵, Fig. 5, is provided, pivoted to the hopper O, as at O⁶, and controlled by a spring O⁷. Normally this catch O⁵ is held in the position shown in Fig. 5, but when turned down, as indicated in dotted lines, the catch passes through an

opening O^8 in the front of the hopper O and cuts off communication between the hopper O and the trough P .

The operation of the machine above described is as follows: Assuming it to be in the position shown in Fig. 1—that is to say, the plunger R is just about to move forward, the cam D has just lifted the finisher L out of contact with the cigarette in the holder F , and the hexagonal plates G' of the retaining device G have turned and presented a fresh moist edge up through the opening J' in the plate J . The shaft C now rotates in the direction of the arrow in Fig. 2, and the following operations take place: The plunger R , acted upon by the cam D^4 , advances and forces a fresh cigarette from the trough P into the holder F and ejects the cigarette previously contained therein. A strip of material being placed upon the moist edges of the hexagonal plates G' is carried by them under the action of the cam D' beneath the revolving felt roller M^{10} , which is supplied with paste from the cylinder M' , and delivers it onto the strip beneath it. The pasted strip is then carried by the continued action of the cam D' under the end of the cigarette in the holder F , and the lifting device K , which has been depressed by the action of the spring-rail G^{12} upon its hook K^3 , is now released and springs up and separates the strip of material from the retaining device G , lifting the strip upward and attaching the end of it to the cigarette in the holder. The lifting device K then recoils to its normal position, leaving the strip upon the cigarette. Shortly after the rise of the lifting device K the finisher L is allowed to fall through the action of the cam D . Continued rotation of the shaft C causes the retaining device G to move back again and to rotate one step under the action of the spring H , and simultaneously the cigarette revolves with the holder F and winds up upon itself the pasted strip of material, which is smoothed as it revolves by the finisher L . The finished cigarette is now ejected by a fresh one, and the process is continued.

The paste for attaching the strips to the cigarette is placed in the cylinder M' and is gradually forced out from the slot M^6 onto the felt roller M^{10} by the action of the piston M^2 , which is urged forward, as previously described, by the ratchet-wheel M^5 , mounted upon the screwed collar M^4 . The paste is distributed over the felt roller M^{10} by the aid of the curved plate M^{11} .

It is obvious that many alterations may be made in the construction of machines according to this invention without departing from its spirit—for instance, the retaining device

need not necessarily be hexagonal, but may comprise any arrangement of surface or surfaces having either corrugations, depressions, grooves, holes, or other accommodation to receive the lifting device, which is of course varied in construction according to the design of the retaining device. 65

It will be appreciated that several of the distinctive features of the machine herein described and illustrated may be applied in a more or less similar manner, and such applications would be considered within the scope of the present Letters Patent. One such application would be the employment of the pasting device M in a cigarette-making machine for pasting the edges of the paper. 70 75

I claim—

1. A machine for applying mouthpieces to cigarettes comprising a support or retainer 80 for the strips, means for imparting a reciprocating movement thereto, combined with an interworking-finger device, K , for lifting the strips from said retainer, and means for wetting the retainer. 85

2. A machine for applying mouthpieces to cigarettes comprising a support or retainer for the strips, means for rotating said retainer and for imparting a reciprocating movement thereto, combined with an interworking-finger device K for lifting the strips from said retainer, and means for wetting the retainer. 90

3. A machine for applying mouthpieces to cigarettes comprising a support or retainer for the strips, means for rotating said retainer 95 and for imparting a reciprocating movement thereto, combined with an interworking-finger device K for lifting the strips from said retainer, a revoluble holder for the article to which the strip is applied, and a finishing device for smoothing the strip after its application to the article carried by the revoluble holder. 100

4. In a machine for the purpose described, the combination of a reciprocating frame, a 105 revolving support or retainer carried by said frame, means for limiting the rotary movement of said retainer, an interworking-finger lifting device K controlled by the movement of said frame for lifting the strips from the 110 retainer, means for supplying a coating to the strips, a revolving holder for the article to which the strip is applied, and a finishing device for smoothing the strip after it is applied to the article, substantially as set forth. 115

In testimony whereof I have hereto set my hand in the presence of the two subscribing witnesses.

JOSEPH SAMUEL BEEMAN.
